UNITED STATES PATENT OFFICE.

LOWELL D. ANDRUS, OF MINNEAPOLIS, MINNESOTA.

SCHOOL-DESK.

1,237,145.

Specification of Letters Patent. Patented Aug. 14, 1917.

Application filed January 19, 1917. Serial No. 143,355.

To all whom it may concern:

Be it known that I, LOWELL D. ANDRUS, a citizen of the United States, residing at Minneapolis, in the county of Hennepin and State of Minnesota, have invented new and useful Improvements in School-Desks, of which the following is a specification.

This invention relates to desks of the type generally used in schools, colleges and the like.

The object of the invention is to provide a desk with a compartment intended to receive and hold books and the like, which, is so positioned that it may be within convenient reach of the pupil or user of the desk.

A further object of the invention is to provide a desk wherein a book compartment is constructed in such a manner as to protect the books and to prevent the accumulation of dirt and dust therein, in order that the compartment may be maintained in a cleanly and sanitary condition.

Another object of the invention is to provide a desk capable of being adjusted to suit children of various sizes in order that it may be positioned to the best possible advantage, thus preventing the necessity of the user working in a bent or cramped position, and by this means promoting the health, convenience and welfare of the children.

A still further object is the provision of a desk, which, is neat and attractive in appearance and which may be easily and quickly adjusted, the adjusting means permitting the amount of adjustment being determined and when adjusted may be securely locked in position.

With the above and other objects in view the invention consists of the following combination and arrangement of parts, herein-after more fully described and illustrated in the accompanying drawings, in which;

Figure 1 is a side elevation of a single pedestal desk constructed in accordance with the present invention and showing the book compartment in section, the lid thereof being shown raised by dotted lines;

Fig. 2 is an enlarged detail vertical sectional view through the adjustable pedestal, showing the means of adjusting and locking the desk to different heights; and

Fig. 3 is a side elevation of another form of desk, illustrating the method of constructing the book compartment with a desk of this type.

Fig. 4 is a perspective view of a modified form of desk; and

Fig. 5 is a fragmentary sectional view on the line 5—5 of Fig. 4, illustrating the method of adjusting this form of desk.

Referring more specifically to the drawings similar characters of reference denote corresponding parts throughout the several views.

As shown in Fig. 1 the desk consists of an inclined top 10 which is supported by a single pedestal 11, secured to the top 10 preferably by means of a bracket 12, which is shown as secured to the underside of the said top, this bracket also forming a means for securing the pedestal thereto. The compartment which is indicated at 13 is preferably co-extensive with the front edge of the top and extends below the same a sufficient distance to provide for the reception of books of the size of ordinary text books.

One side of the compartment extends above the top of the desk as shown at 14, and has hinged thereto as at 15 a lid 16. This lid is provided with an L-shaped strip 17 along its lower edge to form a stop for contact with the upper edge of the bracket 12. The arrangement of the upper portion of the compartment 13 permits the books which are arranged therein upon their ends to be sufficiently exposed in view of the pupil to enable him to select the one desired, without searching beneath the top of the desk, as is usual in the type of desk constructed with a horizontal book compartment.

When the books are arranged with the tallest one at the rear of the compartment, all of the various books may be exposed to view to permit the ready selection of the one desired. The bottom of the compartment is formed of a perforated or reticulated member 18, so that should dust or dirt enter the compartment it will readily sift through.

In order to permit the top of the desk to be adjusted to suit persons of various sizes, the pedestal 11 is composed of telescopic sections 19 and 20, the section 19 being secured to or formed integral with the front 12. The said section 19 is adjustable in the section 20, and for this purpose is provided with adjusting teeth 21, these teeth being spaced at a distance between centers of about one-half an inch, in order that the amount of adjustment may be determined by moving the section 19 the desired number of teeth. Secured within the section 20,

in the path of the teeth 21 is a spring pawl 22, which is provided with a tooth 23 for engagement with the teeth 21. Also carried by the section 20 is a locking screw 24, the shank of which is positioned to engage the rear of the tooth 23 for the purpose of locking the section 19 in its adjusted position.

Various changes in the form and proportion of the invention may be made, as for example the book compartment may be arranged along one side of the top 10, or it may be applied to a type of desk different from the one just described. In Fig. 3 there is illustrated one of such different type, the compartment being secured within the side standards 25 of the desk top 26 and the back of the seat for the pupil just in front being secured against the front side of the book compartment.

It is of course understood that the pedestal 11 may be applied to chairs used in connection with the adjustable desk, or that any other adjustable form of chair may be used.

In the modification shown in Figs. 4 and 5, there is illustrated a desk supported upon adjustable side standards 30. These standards comprise a stationary member 31 and an adjustable member 32. The stationary member includes spaced legs 33, which are joined together by connecting bars 34, the topmost connecting bar being provided with a vertical member 35, which, together with the extended ends 36 of the legs 33 form projecting portions which are adapted to be engaged by the tubular members 37 of the adjustable member 32 of the side standards. The member 35 is formed with teeth 38, after the manner of the teeth 21 previously described, and these teeth are adapted to be engaged by a spring pawl 39 which is secured to and projects through an opening 40 formed in the central tubular member 37. This central member 37 is provided with a yoke 41, in which operates a set screw 42 for locking the side standards

in their adjusted position. The adjustable member 32 is secured to the underside of the top of the desk by means of the bracket 43, which is formed with sockets 44 to receive each of the tubular members 37. The desk top 45 is provided with a book compartment 46, similar to the one described in connection with the preceding form of desk, the said compartment being provided with a hinged lid 47 as before explained. In Fig. 4 of the drawings there is illustrated the idea of book arrangement to which this style of desk is adapted, the said arrangement permitting all of the books to be viewed for the purpose of permitting a ready selection.

From the foregoing description when taken in connection with the accompanying drawings it is believed that the objects and construction of the invention will be apparent, and further description is deemed unnecessary.

Having described the invention, what is claimed is;

1. The combination with a desk, of an adjustable pedestal comprising telescopic sections, adjusting teeth formed upon one of said sections, a spring pawl carried by the other section for engagement with said teeth and a locking screw carried by the last mentioned section and engaging said pawl to lock said sections in their adjusted position.

2. The combination with two members telescopically arranged, of corrugations carried by the inner member, the outer member being provided with an opening, a resilient element removably secured upon the outer member, a detent carried by the resilient element and adapted to extend through said opening for engagement with said corrugations and an adjusting screw engaging the resilient element to hold the members in adjusted position.

In testimony whereof I affix my signature.

LOWELL D. ANDRUS.
